PHONOGRAPH TONE ARM

Melvin H. Boldt, Glenview, Ill., assignor to Zenith Radio Corporation, Chicago, Ill., a corporation of Delaware

Filed Jan. 25, 1965, Ser. No. 83,555

Term of patent 14 years

(Cl. D26—14)

FIG. 1

FIG. 2

FIG. 3

FIG. 4

FIG. 5

FIG. 6

FIG. 7

FIG. 8

FIGURE 1 is a top plan view of a phonograph tone arm, showing one form of my new design wherein a curved elongated tubular arm interconnects a generally rectangular pick-up cartridge housing, having opposite sidewalls which are cut away to expose the pick-up cartridge, and a streamlined upwardly stepped rear casing;

FIGURE 2 is a left side elevational view of the form shown in FIG. 1, the right side being substantially a mirror image thereof;

FIGURE 3 is a fragmentary rear elevational view of the form shown in FIG. 1;

FIGURE 4 is a fragmentary right side elevational view of the form shown in FIG. 1, to an enlarged scale;

FIGURE 5 is a front elevational view of the form shown in FIG. 1, to an enlarged scale;

FIGURE 6 is a top plan view of a phonograph tone arm, showing another form of my new design wherein the pick-up cartridge housing is wider and shorter than in the form of FIG. 1, the tubular arm joins the rear casing eccentrically, and the rear casing is shorter in overall height and more narrowly stepped than in the form of FIG. 1;

FIGURE 7 is a left side elevational view of the form shown in FIG. 6, the right side being substantially a mirror image thereof; and

FIGURE 8 is a fragmentary rear elevational view of the form shown in FIG. 6.

I claim:

The ornamental design for a phonograph tone arm, substantially as shown and described.
